DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent Office makes no assertion as to the novelty of the disclosed subject matter.

14 Sheets Drawing, 25 Pages Specification

A Centralized Memory Access Module (CMA) that provides a means whereby the associated Data Processing Subsystem (DPS) configuration having up to twelve Requester Modules (RM0-RM11) may be multiplexed or interfaced with up to eight Memory Modules (MM0-MM7) is disclosed. The CMA is comprised of an array of groups of printed circuit cards that are mounted on a single panel for back panel wiring. The CMA is comprised of twelve similar Requester Groups R0-R11 and eight similar Memory Groups M0-M7. Each Requester Module and its associated power supply PS are wired to only its associated Requester Group in the CMA, e.g., RM11 is wired to only R11 in the CMA, and each Memory Module and its associated power supply PS are wired to only its associated Memory Group in the CMA, e.g., MM0 is wired to only M0 in the CMA. Thus, each Requester Module and its associated Requester Group in the CMA and each Memory Module and its associated Memory Group in the CMA are functionally independent of each other such that power failure in one of the modules affects only its associated group in the CMA whereby failure of one or more but not all of the modules does not cause DPS failure. The logic design of the groups that make up the CMA isolate all data, address, control and power signals from each other group and from the other modules while having a common ground bus and intercouples data, address and control signals between one Requester Module and one Memory Module, all under control of the associated Requester Group and Memory Group.

1. ALL TIMES IN NANOSECONDS AT CMA INTERFACE AND ARE SPECIFIED FROM THE ACTIVE (SET) THRESHOLD LEVELS.
2. HIGH SIGNAL LEVEL IS THE INACTIVE (CLEAR) STATE (EXCEPT "CLEAR REQUEST" AND "CLEAR ACTIVE"); LOW SIGNAL LEVEL IS THE SET STATE (EXCEPT "CLEAR REQUEST" AND "CLEAR ACTIVE").
3. SLASH SHADING INDICATES EITHER SET OR CLEAR SIGNAL LEVEL IS APPROPRIATE.

This detailed logic diagram illustrates the internal structure of a Data Gating Card. The circuit is organized into several functional blocks:

- Input and Control:** The diagram shows various control signals such as **EN RII ADDRS & WR DATA → MO**, **EN RII CONTROL ENS → MO**, and **EN RII RD DATA → MO**. These signals are processed by logic gates (e.g., AND, OR, NOT) to generate internal control signals like **MO CLR ACT FF's**, **MO CLR REQ FF's**, and **RMI MEM REQ MO**.
- Priority Network:** A central block labeled **MO/RO-RII PRIORITY NETWORK** contains a complex arrangement of logic gates and flip-flops. It includes a **REQ. FF.** and an **ACT. FF.** to manage requests and active states. The network is interconnected with various bus lines.
- Memory and Bus Control:** The circuit includes a **MMO DATA/ADD CABLE 30** and a **MMO DATA GATING CARD**. It features a 30-bit bus structure with **BIT 0** and **BIT 31** as major segments. The bus is controlled by **ODD R's** and **EVEN R's** for reading and writing data to memory.
- Output and Feedback:** The circuit includes several output paths labeled **RII → MO** and **RO → MO**, indicating bidirectional data exchange between the priority network and the memory.
- Timing and Addressing:** Address lines **102**, **104**, **106**, **108**, **110**, **112**, **114**, **115**, **116**, **117**, **118**, **120**, **122**, **124**, **130**, **132**, **134**, **136**, **138**, **140**, **142**, **144**, **146**, **148**, **150**, **152**, **154**, **156**, and **158** are used for memory addressing and control.
